US0D1074898S

(12) United States Design Patent (10) Patent No.: US D1,074,898 S
(45) Date of Patent:  May 13, 2025

(54) GOLF BALL DISPENSER

(71) Applicant: Topgolf International, Inc., Dallas, TX (US)

(72) Inventors: Brian David Burdette, McKinney, TX (US); Andrew David Macaulay, Dallas, TX (US); Clinton Scott Lovejoy, Dallas, TX (US); William Kevin Miner, Frisco, TX (US); Theodore YuChiang Cheng, San Francisco, CA (US); Mark Joseph Semsak, Des Plaines, IL (US); Gabriel Heath Denk, Wylie, TX (US); Justin Dean Pendleton, The Colony, TX (US); Brian Lee Roderman, Plano, TX (US); David Christopher Singer, Austin, TX (US); Clifton Frederick Geisler, McKinney, TX (US); Scott Michael Thibeault, Redwood City, CA (US); Frances Meng Wang, San Francisco, CA (US)

(73) Assignee: Topgolf International, Inc., Dallas, TX (US)

() Term: 15 Years

(21) Appl. No.: 29/936,559

(22) Filed: Apr. 9, 2024

Related U.S. Application Data

(63) Continuation of application No. 29/706,400, filed on Sep. 19, 2019, now Pat. No. Des. 1,027,438.

(57) CLAIM

The ornamental design for a golf ball dispenser, substantially as shown and described.

DESCRIPTION

FIG. 1 is a perspective view of the golf ball dispenser.
FIG. 2 is a front view of the golf ball dispenser.
FIG. 3 is a back view of the golf ball dispenser.
FIG. 4 is a left side view of the golf ball dispenser.
FIG. 5 is a right side view of the golf ball dispenser.
FIG. 6 is a top view of the golf ball dispenser; and,
FIG. 7 is a bottom view of the golf ball dispenser.
The broken lines shown in the figures illustrate portions of the Golf Ball Dispenser and form no part of the claimed design.

1 Claim, 7 Drawing Sheets
